U.S. PATENT DOCUMENTS

3,635,174 1/1972 Ball et al. ..... 312/223 X
3,873,758 3/1975 Van Gessel et al. ..... 312/223 X

FIG. 1 is a front perspective view of a wiring enclosure for desks showing our new design, the enclosure being broken away to indicate indeterminate length;

FIG. 2 is an enlarged end elevation thereof, the edge of the desk being shown in broken lines for illustrative purposes only.

The top, bottom and rear surfaces of the enclosure are plain flat surfaces.
